ELECTRICAL APPARATUS

Raymond P. Lansing, Montclair, N. J., assignor, by mesne assignments, to Bendix Aviation Corporation, South Bend, Ind., a corporation of Delaware

Original application November 4, 1930, Serial No. 493,397. Divided and this application February 27, 1940, Serial No. 321,142

1 Claim. (Cl. 192—02)

This invention relates to electrical apparatus, and more particularly to circuits including electromagnetic elements.

An object of the invention is to provide a novel control of the operation of electromagnetic circuits and parts associated therewith.

As an aid in explaining the utility of the invention, it is illustrated in the accompanying drawings as applied to an engine starter of the type disclosed in my applications, Nos. 247,726 filed January 18, 1928, and 493,397 filed November 4, 1930, Patent No. 2,195,151, March 26, 1940, the present application being a division of the second-named, and the first-named having matured as Patent No. 1,833,948, issued December 1, 1931; but the invention has a wider field of use, and is claimed herein per se, rather than in conjunction with any particular machine which may be subjected to its control.

An object of the invention is to provide a novel compound electromagnet or solenoid and novel means for selectively energizing the component parts thereof.

Another object of the invention is to provide a multiple coil electromagnet and novel control means therefor, whereby one of said coils will be de-energized before the other can be energized.

Another object of the invention is to provide a system including a plurality of electromagnets and novel control means therefor, whereby the energization thereof may be produced in accordance with a predetermined sequential relationship.

Another object is to produce apparatus of the foregoing character which is of relatively simple construction, readily accessible, and positive in its operation.

Other objects and advantages to be derived from the use of the invention disclosed will become evident on an inspection of the following description when made with reference to the accompanying drawings illustrating one embodiment of the invention. It is to be expressly understood however that said drawings are for the purpose of illustration only and are not to be construed as a definition of the limits of the invention, reference being had to the appended claim for this purpose.

In the drawings,

Fig. 1 is a view in elevation, with parts sectioned, of an apparatus embodying the invention;

Fig. 2 is a plan view of certain parts shown in Fig. 1;

Fig. 3 is a longitudinal sectional view of a portion of the switch assembly of Fig. 1, but on a somewhat larger scale; and

Fig. 4 is an end view of portions shown in Fig. 1.

Referring now to the drawings, wherein like reference numerals indicate like parts throughout the several views, and more particularly to Fig. 1, an engine starting mechanism to which the invention is applicable may comprise a casting embodying an inner end section 2, secured as by means of screws 3 to the crank case 4 of the engine, an intermediate section 5 secured to section 2 by screws 6, and an outer end section 7 secured to the intermediate section 5 by means of bolts 8. An end plate or diaphragm 9, preferably integral with the intermediate casting section 5, carries means for supporting a flywheel 12 of relatively small size and light weight, and adapted for high speed rotation so as to store energy therein for cranking the engine.

The energy stored in the rapidly rotating flywheel is transmitted to the engine to be started through a suitable train of reduction gearing, comprising, in the form shown, a stub shaft 13 extending through the hub of the flywheel 12 and rotatable therewith. A small pinion 16 formed on the inner end of the stub shaft 13 meshes with a relatively large pinion 17 formed on the periphery of a bell-shaped member 18, the latter being rotatably mounted on a tubular portion 21 of the transverse plate 9. A small pinion 22 formed on the inner end of the member 18 meshes with a relatively large internal gear 23 which is rotatably mounted by means of a hub portion 24 on a short hollow shaft 25 which extends outwardly from the closed end of a cylindrical member or barrel 26. A pinion 27 formed on the hub portion 24 constitutes a sun gear which meshes with a plurality of planetary gears, preferably three in number, one of which is shown in section at 28, and said planetary gears in turn mesh with a ring gear 29 secured to the casing by screws 30. The planetary gears 28 are preferably mounted on the closed end of the barrel 26 by means of ball bearings 31 having centering sleeves 32 that extend into recesses in the closed end of the barrel 26 and are held in place by screws 33 and a retaining ring 34.

Rotation of the flywheel 12 is transmitted by the train of gearing above described to the barrel 26 and causes rotation of the latter. Rotation of the barrel 26 is in turn transmitted through a yieldable driving connection to a jaw 36 that is adapted to be displaced axially to en-

gage a corresponding jaw 37 secured to shaft 38 of the engine to be started. In the form shown, the yieldable driving connection is constituted by a friction clutch 29 of the multiple disc type which is positioned within the rotatable barrel 26. A plurality of the clutch discs, which are annular in form, are splined at their outer peripheries to the inner surface of barrel 26, and the remaining clutch discs are splined at their inner peripheries to the outer surface of an interiorly threaded nut 40. The clutch discs are held between the closed end of barrel 26 and a flange 41 formed on the nut 40.

Suitable yielding means are provided for maintaining the clutch discs in frictional engagement with one another, which means is preferably adjustable whereby the amount of torque transmitted by the clutch may be varied. For this purpose a plurality of coil springs 42 bear against the flange 41, the springs being held in position by means of pins 43 carried by a spacer ring 44. The tension of the springs may be adjusted by means of an adjusting nut 45 threaded in the barrel 26.

A threaded shaft 46 is positioned within the interiorly threaded nut 40 and is adapted for relative rotary and longitudinal movement therein. The outer end of the shaft 46 carries a stop nut 47 adapted to engage an interior shoulder on the nut 40 to limit the longitudinal movement of the shaft, and a portion of the shaft adjacent its inner end is provided with longitudinal splines which engage corresponding splines formed on the interior of a hub portion 48 formed integrally with the jaw 36. A light coil spring 49 is interposed between the shaft 46 and the jaw 36, the outer extremity of said spring being preferably seated in a recess formed in the shaft.

The novel means employed for axially displacing the jaw 36 to engage jaw 37 comprises, in the form shown, a rod 50 passing centrally through the hub 25, barrel 26, shaft 46 and jaw 36, and is provided intermediate its ends with a shoulder 51 engaging the outer end of the shaft 46 and on its inner end with a nut 52. The rod 50 is adapted to be displaced by novel mechanism extending externally of the starter casing, such mechanism constituting an important part of the present invention to be described more fully hereinafter.

It is desirable to provide means whereby the engine may be cranked and started by hand, and in the present instance said means embodies a hand cranking shaft disposed substantially at right angles to the longitudinal axis of the starter and drivably connected with the reduction gearing near its low speed end by the provision of a suitable gear (not shown) adapted to mesh with bevel gear 53 mounted on the end of shaft 25; the actuating gear being carried in the usual manner by the casing 5, on a cranking shaft projecting outwardly from the starter casing and provided with a suitable hand crank whereby the bevel gear 53 may be rotated to drive barrel 26 through the train of gearing above described.

The means for cranking and accelerating the flywheel 12 by power, in the embodiment shown, comprises the usual electric motor mounted in section 59 of casing 7 and having the end of its armature shaft 60 provided with a threaded portion 61 engaging a correspondingly internally threaded clutch member 62 normally held out of engagement with a complementary clutch

member located within the housing 63 and operatively secured to the flywheel 12 to rotate the latter when the screw shaft 61 is moved forward by the rotation of clutch member 62 and shaft 60 in response to energization of the motor.

The novel means for controlling the engagement producing members 50, 51 and 36 to produce cranking of the engine shaft 38 after the flywheel has been accelerated and the motor 59 de-energized, comprises in the embodiment shown an electro-magnetic device 70 mounted by suitable means upon the member 71; the member 70 containing two coils 72 and 73 with which are associated a pair of magnetizable cores 75 and 76 and a plunger rod 74 secured to the core piece 75 by suitable means as indicated at 76' so as to be movable toward the fixed pole piece 75a upon the occurrence of a similar movement of the core piece 75 in a response to the magnetic pull exerted by the coil 73 upon energization thereof by the means to be described. The members 75 and 76 being keyed one to the other, as shown at 77, energization of coil 72 will cause a reverse movement of plunger rod 74, toward pole piece 76a.

Means are provided for transmitting a longitudinal movement of the plunger rod 74 to the shaft 50 and member 36 to produce engagement between the latter member and the engine member 38. As shown in Figs. 1 and 2 such means preferably includes a rocker arm 78 adapted to swing about a fulcrum or fixed pivot member 79 mounted upon the member 70, the arm 78 connecting at one end with the plunger 74 through a suitable connecting member 83. The other end of arm 78 is shown as pivoted by suitable means 80 to an adjustable link 81 which in turn is connected by suitable lost motion pivot means to one end of a bell crank member 82, the central portion of which is secured to the upper end of a rod 84 which extends vertically through the upper wall of casing 5 in which it is guided by a suitable boss or hub 86, the lower end of the rod being provided with a shifting fork 87 adapted to receive a pin 88 extending through a suitable opening in shaft 50.

From the foregoing it will be apparent that the connecting members just referred to will transmit the longitudinal displacement of the plunger rod 74 to the shaft 50 to cause a corresponding displacement thereof, whereupon the driving member 36 is resiliently urged into driving engagement with the jaw 37. A manually operable rod 82' may be linked to the bell crank 82 as indicated in Fig. 2, to permit actuation of the engaging means by hand when desired.

Referring further to the means associated with the plunger rod 74, it is desired to provide means normally tending to maintain the rod 50 in the position shown in Fig. 1, in which position the member 36 is out of engagement with the member 37. As shown, such means comprises preferably a coiled spring 90 mounted coaxially with a larger spring 91 in the thimble member 92, the opposite end of the spring 90 pressing against the end of the plunger rod 74 and acting to maintain the plunger 74 normally in the central position indicated.

In addition to the function of actuating the members 50 and 36, the plunger rod 74 has an additional function of controlling the means for energization of the flywheel actuating motor. As shown in Fig. 1 such means preferably comprises a circuit controlling switch plate 95 mounted near the outer end of plunger rod 74

and movable into contact with the stationary contact members indicated at 96 and 97 and connected to the terminal posts 98 and 99 respectively, constituting terminals for the conductors 100 and 101, the latter leading to the post 102 of motor 59 and the former being connected to a suitable source of current, represented at 103 in Fig. 3.

From the foregoing it will be evident that a displacement of the member 74 to the left (on the actuation of means to be described) as viewed in Fig. 1 will produce a corresponding movement of the member 95 into engagement with the contacts 96 and 97, thereby closing a circuit to energize the motor 59, the circuit being traceable in Fig. 3 along a path starting from the source 103 and passing by way of conductors 104 and 100 to terminals 98 and 99, thence by way of conductor 101 to the windings of motor 59 and thence to the "ground" by way of conductor 105. The lost motion between link 81 and crank 82 is so arranged that crank 82 will not be moved when member 74 moves from its neutral position to the left (Figs. 1 and 2) to cause engagement of contacts 95, 96 and 97, whereas upon movement of member 74 to the right the lost motion will be taken up and crank 82 will be rotated to cause engagement of clutch 36, 37.

The means for controlling the alternate energization of coils 72 and 73 preferably comprises a switch structure designated generally by the reference character 109 and including two sets of stationary contact members shown at 110, 111, 112, and 113, the former two being adapted to be bridged by the collar 115 of suitable conducting material and the latter two being adapted to be bridged by the collar 116, the circuits through the said members being normally open by reason of engagement with the insulated portions 117 and 118, respectively, the members 117 and 118 being normally held in the positions indicated by the actions of springs 119 and 120. Although the actuating rod 231 of the switch extends loosely through the contact assemblies 115-118 and 116-117, longitudinal movement of the said actuating rod 231 nevertheless causes a corresponding longitudinal movement of either the contact assembly 115-118 or the contact assembly 116-117, depending upon the direction of motion. This is accomplished by reason of the interposition of thrust elements 233 and 234 (shown best in Fig. 3), loosely mounted on rod 231, but having flanges which abut a transversely disposed pin 232 passing through the rod 231 and shiftable therewith. At their outer ends the thrust elements 233 and 234 abut the contact assemblies 116-117 and 115-118 respectively, wherefore movement of the pin 232 to the left causes shifting of contact assembly 116-117 to the left through the agency of the thrust element 233; and, of course, the thrust element 234 will produce a corresponding shifting of the contact assembly 115-118 to the right in response to a rightward movement of the rod and pin 231 and 232; the movement in each direction being limited by the stop plates 236 and 237 constituting stationary elements of the supporting housing.

With the foregoing in mind, it will be apparent that upon movement of the operating member 122 to the right as viewed in Fig. 1 engagement will be effected between the members 115, 110 and 111, thereby closing a circuit to the end coil 72, the circuit passing from the source 103

5 by way of conductors 104, 100 and 121 to the coil 72, then by way of conductor 124 to the terminal 125, contact 111, collar 115, contact 110, terminal post 126 and thence by conductor 127 to the ground.

10 Energization of the coil 72 which is thus produced operates to displace the plunger 74 to the left as viewed in Fig. 1 thereby causing the member 95 to bridge the contacts 96 and 97. This in turn closes the circuit to the motor 59 previously traced. The resulting rotation of the armature shaft 60 of the motor causes the clutch member 62 to rotate and move forward into engagement with the complementary member to drive the flywheel 12, the rotation of the flywheel being transmitted through the train of reduction gearing above described to barrel 26 and, through the friction disc 28, to the shaft 46 and member 36.

15 As soon as the flywheel has reached the desired speed the member 122 is again manually actuated, being pushed to the left to cause a bridging of the contacts 122 and 113 by the member 116. At the same time, this movement withdraws the member 115 from the contacts 110 and 111. This withdrawal operates to break the circuit to the coil 72 which in turn permits the spring 90 to force the contact maker 95 out of engagement with the contacts 96 and 97 thereby interrupting the circuit to the motor 59 and de-energizing the said motor. At the same time the engagement of collar 116 with the members 112 and 113 operates to close a circuit to the coil 73, this circuit being traceable in Fig. 3 along a path leading from the source 103 by way of conductors 104 and 129 to the contacts 112, 116 and 113, thence by way of conductor 130 to the winding of coils 73, from which point the circuit returns to the "ground" by way of conductor 131. This energization of the coil 73 serves to draw the plunger 74, to the right thereby actuating the rod 50 and moving the jaw 36 into driving engagement with the jaw 37 in the manner above explained.

20 The complete assembly, as shown in Fig. 1, preferably includes a circuit interrupting device commonly known as a vibrator, and the means for actuating the said vibrator coincidentally with the energization of solenoid 73. Such vibrator is shown in Fig. 1 as mounted on a suitably supported casing 150, containing a core or plunger 151 adapted to be actuated by the creation of magnetic forces in the coil 152, such coil consisting of the usual primary and secondary windings; the construction being such that upon each interruption of the circuit at the contacts 156 and 157, the resulting breakdown of the magnetic field of the primary winding of coil 152 causes the passage by induction of a relatively high potential current through the secondary winding of coil 152, thereby creating a jump-over spark at the ignition points in the engine.

25 Various changes may be made in the construction, arrangement and inter-relation of the parts constituting the invention without departing from the spirit thereof, it being understood that although only one embodiment of the invention has been illustrated the same is not limited to the form shown. Reference will therefore be had to the appended claim for a definition of the limits of the invention.

30 This application is a division of copending application No. 4,716 filed February 2, 1935, which is, in turn, a division of application No.

493,397, above identified; the last named application having matured as Patent No. 2,195,151, granted March 26, 1940.

What I claim is:

The combination, with a pair of clutch elements, of means including an electric motor for rotating said clutch elements, means including a solenoid plunger for engaging one of said

clutch elements with the other, to cause both to rotate with said motor, and means including a switch element carried by said solenoid plunger for conducting current to said motor to cause rotation thereof prior to engagement of said clutch elements.

RAYMOND P. LANSING.
